UNITED STATES PATENT OFFICE

JOHN FETZER, OF PITTSBURGH, PENNSYLVANIA

TUNNEL KILN

Application filed January 11, 1930. Serial No. 420,107.

This invention relates to continuous tunnel kilns wherein brick or other clay products are dried, burned or fired and cooled during their intermittent progression therethrough.

5 This invention more particularly relates to tunnel kiln wherein the method of arranging or stacking the brick or other articles to be fired in relation to the walls and heat application of the kiln constitutes an important

10 feature as will be more fully explained hereinafter.

It is among the objects of this invention to provide a method of and apparatus for drying, firing and cooling clay articles adapted to carry out the several steps of the process in a minimum period of time and by the use of a minimum length of kiln, whereby great economy of heat energy or fuel is obtained.

20 Another object of the invention is the provision of means for producing uniform application of heat to all articles passing through the kiln whereby uniformity in the quality of the product is obtained.

25 Another object of the invention is the provision of a kiln which is adapted to dry, fire and cool the articles passing therethrough at a maximum rate without distorting or unduly warping or stressing the articles, where-

30 by a maximum production capacity is obtained from a kiln of a given cross sectional area and length.

These and other objects will become more apparent from a consideration of the accompanying drawing in which like reference characters designate like parts and in which Fig. 1 is a top elevational view partly in section of a kiln embodying the principles herein set forth; Fig. 2 a side-elevational view thereof partly in section; Fig. 3 a cross sectional view taken along the lines III—III of Fig. 1; and Figs. 4 and 5 are top and side elevational views of a portion of the roof showing its hollow tile construction.

45 Referring to Figs. 1 and 2 of the drawing, the structure therein illustrated comprises a tunnel kiln 1 having doors 2 at each end. The kiln is provided with baffle plates 3 and 4 at the sides and top, respectively, to form a plurality of chambers. The plates are

hinged in a suitable manner to swing in the direction of movement of the work which is towards the rear of the kiln, and they are provided with springs 5 or other suitable means tending to hold them transversely of the top and side walls. Handles 6 are attached to the plates and extend through the kiln wall for the manual operation of the plates when desired. A plurality of openings shown by dotted lines 7 and provided with covers 8 are located in the side walls so that the articles passing through the kiln may be inspected from time to time. At 9, are a number of openings leading through the kiln walls to as many ash pits shown by dotted lines 10, said ash pits having covers 11 for the ready removal of ashes without interference with the operation of the kiln. At both sides of Fig. 1 are fire boxes 12 shown in side elevation in Fig. 3. An air blower 13 is mounted at the rear of the kiln and is provided with a pulley 14 for connection with a prime mover, such as a motor (not shown). A hopper 15 extends across the top of the kiln and is provided with a feed mechanism 16, to supply powdered fuel to the inside of the kiln. An exhaust fan 17 draws the products of combustion to the front end of the kiln.

Throughout the length of the kiln is a track 18, Figs. 2 and 3, which is elevated at the front end to provide a declining runway towards the discharge end of the kiln. Wheeled trucks 19 constitute the work supports and the trucks are arranged end to end to form a continuous conveyor for the articles passing through the kiln.

When a truck load of articles is charged into the kiln at the front end, a truck load of fired articles is simultaneously discharged at the rear end. Since the connected truck bodies form a passage along the entire length of the kiln, baffle plates 20 are provided underneath the trucks, to prevent such passage operating as a flue. The plates 20 extend across the entire width of the kiln between the side plates 21 of the trucks, Fig. 3, and to the bottom or floor 22. In this manner they function to scrape the bottom and prevent accumulation of ashes which are scraped into

the ash pits 10 by the movement of the trucks through the kiln.

The roof of the kiln may be constructed of hollow tile 24, Fig. 5, which are supported by bars 25, Fig. 4, that pass through the hollow tile and rest on the side walls of the kiln as at 26. The roof is strengthened by fire clay placed between adjacent tile.

The brick is stacked on the truck to completely fill the cross sectional area of the kiln above the trucks 19 and is arranged in staggered relation forming a checker work of flues. The truck bodies are provided with fire clay or brick bottom 23 Fig. 3, on which the articles to be fired are stacked.

15 The operation of the kiln in the firing of the brick or other clay articles mounted on the movable conveyers, as described, is briefly as follows:—

20 Combustion is established in the fire boxes 12 and articles to be fired are charged into the front end of the kiln and are moved toward the discharge end in the direction of the fire boxes. As the articles to be fired accumulate rather slowly and are intermittently charged into the kiln, the trucks will move slowly to the portion of the kiln between the baffle members 3 and 4. This portion constitutes the firing chamber. The exhaust fan 17 is operated to set up a draft from the firing chamber through the checkerwork of brick toward the charging end of the kiln whereby the green clay is subjected to a drying temperature and is preheated preliminary to its 35 passing into the firing chamber between the spaced baffles.

When the kiln has been filled to the extent that the charge approaches the fire boxes 12, the clay articles have attained a red heat and combustion may be maintained by feeding powdered fuel through the feed mechanism 16 of the hopper 15 directly on the loaded trucks and the fire box may be extinguished. The feed mechanism 16 may be mechanically operated by a suitable driving mechanism (not shown). When the charge of the kiln advances beyond the fireboxes into the end chamber, the blower 13 may be operated to force a supply of air through the checkerwork or flues of the hot brick into the firing chamber. The air from the blower cools the brick and is preheated before passing into the firing chamber to support combustion, and as previously explained, the products of combustion are drawn through the checkerwork of the incoming brick by the exhaust fan 17 to dry and preheat said brick. It is obvious that the same effect can be produced by opening the doors at the respective ends of the kiln to set up a draft through the entire chamber from the discharge end to the charging end, this being possible for the reason that the charging end is slightly elevated as previously explained to provide for the movement of the charge through the kiln by

gravity and the circulation is further established for the reason that the articles are hot at the discharge end of the kiln and cold at the charge end, thereby inducing circulation or draft from the hot end to the cold end. 70 However, the use of the blower and exhaust fans is preferred as a means of obtaining positive regulation.

By arranging the articles in staggered relation to form a series of flues in the heated chamber of the kiln, such articles may be continuously fired in a minimum length of time and with uniformity of quality. It is further evident that by utilizing the heat of the fired articles for preheating the air entering 75 the firing chamber, a minimum amount of fuel is employed and by drawing the products of combustion through the articles passing into the kiln to dry and preheat the same, the time of firing and cooling the brick is 80 reduced to a minimum.

It is further evident that such kilns may be advantageously utilized in the firing of clay articles of various description, though more particularly for firing brick, tile and the like, which more readily permit stacking to 90 form the aforementioned checkerwork formation.

Although one embodiment of the invention 95 has been herein illustrated and described, it will be obvious to those skilled in the art that various modifications may be made in the details of construction, for example in the substitution of the work carrying means or the substitution of other parts than those 100 specified, without departing from the principles herein set forth.

I claim herein as my invention:

1. In a tunnel kiln for firing clay articles, a longitudinal chamber having end closures, 105 a plurality of wheeled trucks for supporting the articles in their passage through said chamber, baffles depending from the trucks to the bottom of said chamber, and baffles projecting from the top and side walls of the chamber, said baffles dividing said chamber into separate heating and cooling zones.

2. In a tunnel kiln, a heating chamber, conveying means in said chamber, a plurality of ash-pits in spaced relation in the floor 115 of said chamber and means movable with said conveying means for cooperation with the floor of said chamber to discharge the ashes accumulating on said floor into said pits.

3. In a tunnel kiln for firing clay articles, 120 a longitudinal chamber having yielding baffles dividing said chamber into a drying, firing and cooling zone, a continuous conveying means in said chamber of substantially the width of said chamber and adapted to 125 support the articles to be treated thereon in a manner to substantially fill said chamber, a combustion zone in the firing portion of said chamber, means for drawing air into the cooling zone of the chamber in contact 130

with the heated articles and conducting said preheated air to the combustion or firing zone and means for drawing the products of combustion through and around the articles being treated towards the charging or drying zone of said chamber, said cooling air and products of combustion being drawn continuously through the treating portion of said chamber in contact with the articles to be treated.

10 4. In a tunnel kiln for firing clay articles, a longitudinal chamber, a yielding baffle disposed therein dividing it into a drying, firing and cooling chamber, combustion chambers provided externally of said treating chamber intermediate the preheating and cooling chambers, and a hopper disposed at the top of said treating chamber to feed fuel on the material passing through said chamber, means for drawing air around the heated articles at the cooling end of said chamber and conducting the preheated air to support combustion in the firing chamber and independent means for withdrawing the products of combustion through the preheating chamber.

25 In testimony whereof I have hereunto set my hand this 10 day of January, 1930.

JOHN FETZER.
